UNITED STATES PATENT OFFICE.

ALEXANDER R. DUFF, OF ONEIDA, NEW YORK, ASSIGNOR OF TWO-THIRDS
TO PETER LEWIS, OF SAME PLACE, AND JOHN G. HOFFMAN, OF NEW
YORK, N. Y.

BOLT-CUTTER.

SPECIFICATION forming part of Letters Patent No. 269,271, dated December 19, 1882.

Application filed August 21, 1882. (No model.)

To all whom it may concern:

Be it known that I, ALEXANDER R. DUFF, of Oneida, in the county of Madison and State of New York, have invented a certain new and 5 useful Improvement in Bolt-Cutters, of which the following is a specification.

This improvement consists in the combination, in a bolt-cutter, of an open frame, the two sides of which are rigidly connected together, a stationary cutter secured therein, a sliding cutter extending across the frame, and having its opposite edges fitting in guides in the sides of the frame, two levers pivoted together and to the stock of the sliding cutter, and links connecting said levers with the two sides of the frame, all as particularly herein-after described.

In the accompanying drawings, Figure 1 is a side view of a bolt-cutter embodying my improvement, and Fig. 2 is a longitudinal section of the same.

Similar letters of reference designate corresponding parts in both figures.

A designates the frame of the bolt-cutter, which may be of any suitable metal. This frame has a large opening, and its two sides are rigidly connected together. The two sides are here shown as formed in one casting, and the frame is of **U** shape.

30 B designates a cutter fitted in guides *a* in the frame A, so that it may be adjusted lengthwise thereof. A screw, C, working in a tapped or internally-screw-threaded hole in the frame A, impinges against the back of the cutter B, and serves to adjust it outwardly and to retain it in position when in operation. A screw, D, working in a tapped or internally-screw-threaded hole in the frame A and impinging against one edge of the cutter B, serves to secure it in any position to which it may be adjusted.

B' designates a movable cutter, which is fitted into the guides, and is adapted to move lengthwise thereof when in operation.

45 E designates two levers, which are sever-

ally pivoted to a pair of links, F, which are pivotally connected to the frame A. These levers are pivoted to the stock or shank of the cutter B'. By swinging the free ends of these levers away from each other the cutter B' will be drawn away from the cutter B, and by swinging the said ends of the levers toward each other the cutter B' will be forced powerfully toward the cutter B.

It will be observed that the frame A is made in one piece, with a rounded outer portion and two parallel sides, and that the links F are pivoted to its ends. A cross-piece, G, connecting the sides of the frame near the ends, may be used to stay the sides and prevent them from being spread apart by the action of the levers. One lever, connected by a link or pair of links to the frame A, could be used alone, if, in lieu of its fellow, a rigid extension of the opposite end of the frame is used or some other support employed. Two levers will, however, be preferable.

Obviously the knives or cutters can be easily taken out of the frame and sharpened.

What I claim as my invention, and desire to secure by Letters Patent, is—

1. In a bolt-cutter, the combination of an open frame, A, having its two sides rigidly connected together, a stationary cutter, B, secured therein, a movable cutter, B', extending across the frame, and having its opposite edges fitting in guides in the sides of the frame, two levers, E, pivoted together and to the stock of the movable cutter, and links F, connecting said levers with the two sides of the frame, substantially as specified.

2. The combination of the frame A, the cutter B, fitted to guides in the frame, the screws C D, the cutter B', the levers E, and the links F, pivotally connected to the levers and frame, substantially as specified.

ALEXANDER R. DUFF.
